Primary Examiner — Elizabeth J Oswecki

(57) **CLAIM**

The ornamental design for an open interior delivery box, as shown and described.

DESCRIPTION

FIG. 1 is a front perspective view of an open interior delivery box, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof.

The broken lines in the drawings showing portions of the open interior delivery box are included for the purpose of illustrating environmental structure and form no part of the claimed design.

1 Claim, 14 Drawing Sheets(56)
